UNITED STATES PATENT OFFICE

168,209

WATCH

Ardé Bulova, New York, N. Y., assignor to Bulova
 Watch Company, Inc., New York, N. Y., a corporation of New York

Application November 6, 1951, Serial No. 17,311

Term of patent 14 years

(Cl. D42—8)

To all whom it may concern:

Be it known that I, Ardé Bulova, a citizen of the United States, residing in New York city, in the county of New York and State of New York, have invented a new, original, and ornamental Design for a Watch, of which the following is a specification, reference being had to the accompanying drawing forming part thereof.

Fig. 1 is a front elevational view of a watch showing my new design;

Fig. 2 is an edge view of the watch shown in Fig. 1 and

Fig. 3 is a rear elevational view of the watch.

I claim:

The ornamental design for a watch, as shown.

ARDÉ BULOVA.
